UNITED STATES PATENT OFFICE

RAUL PATERAS PESCARA, OF PARIS, FRANCE

AIR COMPRESSOR

Application filed June 2, 1927, Serial No. 195,980, and in France June 5, 1926.

My invention relates to improvements in air compressors in which the compression takes place in stages and the principal object is to establish a combination of compressing cylinders and pistons arranged in such a manner as to produce a high output and high compression of the gases to be compressed.

A further object of the invention is the 10 adaptation of such an arrangement to the compressors forming the subject of invention of my French Patents No. 627,385, of April 1, 1926; No. 627,386, of April 2, 1926; No. 626,982, of April 7, 1926; No. 628,550, 15 of April 8, 1926; No. 628,563, of April 9, 1926; and No. 628,572, of April 10, 1926.

Still another object of the invention is to 20 arrange the parts so that the independent spaces in which the expansion and compression of an inert gas produces stability of operation of the apparatus, as set forth in the fourth of my French patents above mentioned, if desired, and to utilize the dead space of the cylinders of one of the stages 25 of compression for producing the same result, the principle of which is more fully described in the last of my French patents, above mentioned.

Other objects of the invention will be 30 obvious to those skilled in the art to which the invention appertains in the following description taken in connection with the accompanying drawing in which—

Fig. 1 is a diagrammatic showing of the 35 first embodiment of the invention with the compressor shown in longitudinal section; and

Fig. 2 is a similar view of a modification.

The invention consists essentially in producing 40 compression of the gases in two series of compressing cylinders, whose bores become less from the center of the apparatus toward the extremities thereof, in conjunction with two direct-acting pistons, corresponding on the one hand to the successive bores of the said compressing cylinders and on the other hand adapted to receive a driving impulse in a centrally disposed cylinder common thereto. These various features are 45 so arranged in combination that the said pis-

tons remain completely free of all mechanical transmission destined to transfer the driving energy, with the exception of that which is required for the operation of the accessories of the machine, such as, distribution, ignition and the like all of which is more fully disclosed in the French patents, above pointed out, and to which reference may be had for a fuller description.

Referring to the drawing, and particularly 60 to Fig. 1, a central motor cylinder 12 has disposed in axial alignment at each end thereof a pair of low pressure compressing cylinders 13 and 14, a pair of medium or mean pressure cylinders 15 and 16 disposed in axial alignment with and at the ends of said cylinders 13 and 14 and a pair of high pressure compressing cylinders 17 and 18 disposed in axial alignment at the extremities of said cylinders 15 and 16. 65

A multiple piston is adapted to slide in each series of cylinders and the central motor cylinder 12. These pistons comprise a cylindrical portion 19 and 20 fitted in motor cylinder 12, a portion 21 and 22 fitted in the low 70 compression cylinders 13 and 14, a portion 23 and 24 fitted in the medium compression cylinders 15 and 16 and a portion 25 and 26 fitted in the high compressing cylinders 17 and 18, respectively. 75

The motor cylinder 12 is furnished with admission openings 27 and exhaust openings 28 in order to accomplish the necessary two cycle combustion operations in said cylinder as more fully disclosed in my French Patent 85 No. 626,928 of April 7, 1926, above referred to.

The pistons 21, 22 compress the air drawn into cylinders 13 and 14 through valves 29 and 30 from the atmosphere and push it back through the valves 31 and 32 into a low pressure tank 33. In passing into the said tank this air circulates through tubes 34 and 35 then through coolers 36 and 37 respectively which restores its initial temperature before entering the tank 33 through tubes 38 and 39. 90

In like manner the pistons 23 and 24 compress the air drawn into the cylinders 15 and 16 through the pipes 40 and 41 from the low pressure tank 33 passing through check valves 42, 43 provided for that purpose. The air 100

then circulates through check valves 44 and 45, tubes 47 and 48, coolers 49 and 50 for restoring its initial temperature, pipes 51 and 52 and finally enters the medium pressure tank 46.

5 The pistons 25 and 26 compress the air drawn into cylinders 17 and 18 through pipes 53, 54 from tank 46 through check valves 55 and 56 and drive it through the valves 58 and 59 through tubes 60 and 61 and finally into the high pressure tank 57.

10 It is thought that a further detailed description of the operation is unnecessary in view of the disclosure of the patents, above referred to. The only difference it presents over the operation described therein is the manner of stabilizing the machine which is substantially the same for the compound compressor forming the subject of this application.

15 When the pistons 19, 21, 23, 25 and 20, 22, 24, 26 reach the end of their compressing power stroke, they stop in a position which is substantially that represented in Fig. 1. 20 Their return stroke and the achievement of the engine cycles in cylinder 12, namely the preliminary compression of the explosive mixture in said cylinder is assured by two motive forces; first, the expansion of the compressed gaseous cushions remaining at the 25 end of the stroke in the ends 62, 63, 64, 65, 66, 67 of the respective compressing cylinders 13, 14, 15, 16, 17, 18 which expansion continues in each of said cylinders until neutralized by 30 the intake pressure; and, second, the constant pressure corresponding to the admission of air into each of the compressing cylinders as follows: atmospheric pressure in light pressure cylinders 13, 14; low pressure in medium pressure cylinders 15, 16; and mean pressure in high pressure cylinders 17, 18.

35 As has been indicated in my French Patent No. 628,550 of April 8, 1926, above mentioned, in order to stabilize the apparatus, it is necessary to establish a compensation between the different motive forces during the return stroke so as to overcome the inevitable variations which can take place in the energy transmitted or received by the pistons 19, 21, 23, 25 and 20, 22, 24, 26.

40 In the present apparatus this compensation can be obtained through the medium of the gaseous cushions contained in the spaces 62, 63, 64, 65, 66, 67. It will be noticed, however, that the check valves 58 and 59 of the high pressure cylinders 17 and 18 are disposed on the lateral wall thereof instead of the disposition disclosed in connection with the other cylinders and check valves, in such a 45 manner that the orifices which they control are covered in the event that the pistons 25, 26 move beyond their normal forward stroke and pass their theoretical dead points.

50 Likewise as has been disclosed in my co-pending application just referred to, it will

be remembered that any anomaly altering the equality of the driving force or the resistance which pistons 19, 21, 23, 25 and 20, 22, 24, 26 are subjected to either at the beginning or at the end of their stroke will accordingly cause said pistons to pass their theoretical dead points at the compressor end of the cylinder. Compensation takes place automatically since my method of operation disclosed in my French Patent No. 628,550 of April 8, 1926, above mentioned, corrects for disturbances causing too long a stroke as well as those causing too short a stroke.

55 If said pistons pass the dead point as shown in Fig. 1 they will only be returned by diminished air cushions in spaces 62, 63 and 64, 65 the volume of which becomes smaller and the pressure of which remains constant. The air cushions in spaces 66 and 67 will always include the same mass of air inasmuch as the pistons 25 and 26 will have covered up the check valves. On the other hand the pressure of the air contained in the said spaces will have increased and will furnish energy in expanding superior to that normally produced. It will thus be seen that partial compensation can take place between the diminution of the cushions in spaces 62, 63 and 64, 65 and the enrichment in energy of the air cushions in the spaces 66, 67. This compensation effectively assures the return to normal operation at the end of a small number of reciprocations as soon as the abnormal stroke disappears.

60 The embodiment shown in Fig. 2 is similar to that described in connection with Fig. 1 and provides for the case where the bore of the motor cylinder must be larger than that of the compressor cylinders of the first stage.

65 In order to facilitate a ready comparison between the two embodiments the elements of Fig. 2 corresponding to those of Fig. 1 have been given the same numbers of reference increased by 100.

70 It is thought that a detailed description is unnecessary due to the similarity of the two devices. Suffice it to say that the chief difference between the two embodiments resides solely in the disposition of pistons 121, 122 corresponding to the first stage of compression in concentric relation with respect to motor pistons 119, 120 as pointed out in my French Patent No. 627,386 of April 2, 1926 above referred to in connection with a simple compressing apparatus.

75 Stabilization is accomplished as described in connection with Fig. 1 with the exception that the check valves 158, 159 are disposed in the cylinder heads of high pressure cylinders 117, 118 and independent gaseous cushions are established by means of the annular spaces 168, 169.

80 Many variations in my apparatus may be made by those skilled in the art without departing from my invention, since

What I claim is—

1. In a compound air compressor of the type described, the combination of a motor cylinder, a plurality of compressing cylinders of different diameters mounted coaxially with said motor cylinder at each extremity thereof, a multiple direct-acting free-flying piston fitted in each extremity of said motor cylinder and extending into said compressing cylinders and means associated with said compressing cylinders for producing compression in stages. 70
2. In a compound air compressor of the type described, the combination of a motor cylinder, a plurality of compressing cylinders of different diameters mounted coaxially with said motor cylinder at each extremity thereof, a piston disposed in each extremity of said motor cylinder, said motor cylinder having a plurality of admission openings and a plurality of exhaust openings whereby said pistons may be driven directly by means of internal combustion, a plurality of compressing pistons integral with each of said first mentioned pistons and extending into said compressing cylinders and means associated with said compressing cylinders for producing compression in stages. 75
3. In a compound air compressor of the type described, the combination of a plurality of driving pistons adapted to be driven directly by means of internal combustion, a common cylinder for said driving pistons, a plurality of series of low, medium, and high pressure cylinders connected to said motor cylinder, a plurality of series of corresponding pistons mounted in said compressing cylinders, a low pressure tank and means for connecting it to said low pressure and said medium pressure cylinders, a medium pressure tank and means for connecting it to said medium pressure and said high pressure cylinders, a high pressure tank and means for connecting it to said high pressure cylinders and means associated with said tanks and said compressing cylinders for allowing air to be drawn in from the atmosphere pushed through said compressing cylinders and said tanks and compressed in stages. 80
4. In a compound air compressor of the type described, the combination of a pair of compressing pistons, means for driving said pistons directly by means of internal combustion, including a motor cylinder common to said pistons, said motor cylinder having a plurality of inlet openings and a plurality of exhaust openings and means cooperating with said compressing pistons for producing compression in stages and automatically stabilizing the operation of said pistons. 85
5. In a compound air compressor of the type described, the combination of a pair of compressing pistons each comprising four cylindrical portions of different diameters, a common motor cylinder for two of said cylinders, said motor cylinder having a plurality of inlet openings and a plurality of outlet openings whereby said pistons may be driven directly by the force of an explosion, means associated with certain of said cylinders for producing compression in stages and means including a plurality of valves for collecting the gas thus compressed, said valves being adapted to be covered and rendered ineffective near the end of the stroke of said pistons whereby the operation of the device is automatically stabilized. 90
6. In a compound air compressor of the type described, the combination of a motor cylinder, a plurality of compressing cylinders of different diameters mounted coaxially with said motor cylinder at each extremity thereof, a piston disposed in each extremity of said motor cylinder, a plurality of compressing pistons integral with each of said first mentioned pistons and extending into said compressing cylinders, independent stabilizing means for each of said first mentioned pistons and means associated with said compressing cylinders for producing compression in stages. 95
7. In a compound air compressor of the type described, the combination of a motor cylinder, a plurality of compressing cylinders of different diameters mounted concentrically with said motor cylinder at each extremity thereof, a piston disposed in each extremity of said motor cylinder, said motor cylinder having a plurality of admission openings and a plurality of exhaust openings whereby said pistons may be driven directly by means of internal combustion, a plurality of compressing pistons integral with each of said first mentioned pistons and extending into said compressing cylinders, independent stabilizing means for each of said first mentioned pistons and means associated with said compressing cylinders for producing compression in stages. 100
8. In a compound air compressor of the type described, the combination of a pair of compressing pistons, means for driving said pistons directly by means of internal combustion, including a motor cylinder common to said pistons, said motor cylinder having a plurality of inlet openings, a plurality of exhaust openings, means independent of said compressing cylinders and pistons for automatically stabilizing the operation of said pistons and means cooperating with said compressing pistons for producing compression in stages substantially as described. 110
